UNITED STATES PATENT OFFICE

2,106,234

PROCESS FOR SOLVENT EXTRACTION OF
OILSUlric B. Bray, Palos Verdes Estates, Calif., as-
signor to Union Oil Company of California,
Los Angeles, Calif., a corporation of California

Application February 19, 1934, Serial No. 711,963

5 Claims. (CL 196—13)

This invention relates to the extraction of oils by employing a selective solvent. Although applicable to the treatment of other oils, it refers more particularly to the production of lubricating oil by a selective solvent extraction process.

It has been found that desirable paraffinic hydrocarbons can be separated from the undesirable olefinic, naphthenic and/or aromatic compounds by the use of solvents which selectively dissolve the undesirable hydrocarbons but which exhibit only a very limited solvent power upon the desirable paraffinic hydrocarbons.

When I use the term "paraffinic hydrocarbons" I mean those highly saturated compounds which are present in petroleum and are characterized by a low temperature viscosity susceptibility, i. e., they exhibit a minimum change in viscosity for a given change in temperature. They also are characterized by relative stability to air and sunlight, exhibiting little tendency toward discoloration or sludge formation. This definition is not meant to include those compounds which are usually solid or semi-solid at ordinary temperatures and which are known as "wax" or "petrolatum"; but, of course, it is obvious that my invention is meant to also include the selective extraction of waxy oils. As a matter of convenience hereafter, I will refer to the undesirable components, such as olefinic, naphthenic and/or aromatic hydrocarbons, as the "non-paraffinic" components of petroleum. These fractions are characterized by a relatively high temperature viscosity susceptibility and are relatively unstable to air and sunlight, exhibiting discoloration and sludge formation.

A number of selective solvents for extraction have been found; for example, it has been shown that such materials as aniline, chloraniline, nitrobenzene, dichlorethyl ether, phenol, chlorophenol, cresol and cresol with a small proportion of water, for instance 4%, are highly selective as solvents for the non-paraffinic hydrocarbons. When these solvents are commingled with petroleum or petroleum fractions under the proper conditions of temperature, the undesirable non-paraffinic hydrocarbons pass into solution to a greater or less extent but a substantial proportion of the desirable paraffinic hydrocarbons remains undissolved. The solution of undesirable hydrocarbons and solvent settles to the bottom of the container and forms an extract phase when relatively heavy solvents are employed. The relatively light paraffinic hydrocarbons rise to the top of the vessel and form a raffinate phase. These phases are then readily separable by ordinary

decantation means. The raffinate phase is usually found to contain a small quantity of the selective solvent and the extract phase ordinarily contains a relatively large quantity of the solvent. These fractions may be purified by distillation whereby the solvent is distilled away from the hydrocarbon oils.

In the usual solvent extraction of mineral oil with the above mentioned selective solvents, the separation is not complete. Particularly, all of the paraffinic hydrocarbons, i. e. the more valuable lubricants, are not obtained in the raffinate phase but instead, some of the high grade paraffinic oil fractions are found in the extract phase. Also, the extract phase may contain certain fractions of oil characterized by properties intermediate low and high grade. These fractions are not desired in the final raffinate but are valuable as second grade oils when separated from the fractions of low quality.

It has been known in the solvent extraction art that after making a primary separation of raffinate from extract, additional fractions can be made to separate from the extract phase by one or more reductions of temperature which correspondingly reduce the solubility of these oils of relatively high paraffinity in the extract phase. These oils then form intermediate raffinates which can be separately recovered by decantation from the remaining extract phase. The solubility of oils of relatively high paraffinity in the extract phase can also be reduced by the addition of an anti-solvent thereto, the presence of which causes a phase separation between an intermediate raffinate and remaining extract phase. This intermediate raffinate comprises second grade oil of quality superior to the oil remaining dissolved in the extract phase.

An anti-solvent may be defined as a material which tends to prevent the solution of a hydrocarbon fraction which, except for the presence of the anti-solvent, would be dissolved in the extract phase upon extraction of the oil with a selective solvent. A number of substances are suitable for use as an anti-solvent; for instance liquid normally gaseous hydrocarbons such as liquid ethane, propane or butane, or methyl, ethyl or isopropyl alcohols, methyl cellosolve (mono-methyl ether of ethylene glycol) and other oxygenated compounds such as acetone or methyl acetate. Even water may be used as an anti-solvent when the selective solvent with which it is employed is at least partly soluble therein. One or more of these anti-solvents may be employed.

In some cases, the addition of an anti-solvent

to the extract phase renders temperature reduction unnecessary to separate relatively high quality oil fractions therefrom. In other cases, refrigeration of the extract phase will be necessary but will be less than when no anti-solvent is present. In a solvent extraction process of this character, the expense of refrigeration is a substantial item in the cost of operation. My process lowers this cost.

Under certain conditions, the anti-solvent which may be employed may be a substance which is a selective solvent when employed alone. For instance, there may be mixed with the extract phase to function as an anti-solvent a selective solvent having less solvent power for the higher grade material present therein than the solvent power of the selective solvent originally used to produce the extract. As an example, oil may be treated with chloraniline or a mixture of liquid sulphur dioxide and benzene to obtain an extract phase. These solvents are characterized by high solvent power for higher grade material. To the extract phase thus produced there may be added liquid sulphur dioxide or other solvent having relatively less solvent power for the higher grade material. For this reason and under these conditions, certain selective solvents may be employed as anti-solvents and by their presence in the extract phase the higher grade fractions therein are rejected to form an intermediate raffinate.

I have found that when the anti-solvent employed is a liquid, normally gaseous substance such as liquid propane, butane, sulphur dioxide or the like, the rejection of desirable oils from the extract phase by the presence of said anti-solvent is aided when the pressure is sufficiently reduced in the rejection stage to cause evaporation of a portion of the anti-solvent, thereby reducing the temperature of the mixture of the extract phase and anti-solvent remaining liquid. In this case the liquid, normally gaseous material, for instance ethane, propane, butane or similar substances, not only functions as an anti-solvent to remove the relatively high grade fractions from the extract phase but also operates as an internal refrigerant. After evaporation for internal refrigeration, sufficient amounts of said liquid, normally gaseous material should remain associated in the liquid phase with the extract to function as an anti-solvent.

It is an object of my invention to separate an oil by means of a selective solvent into a raffinate phase and an extract phase and to intermix said extract phase with an anti-solvent to separate an intermediate raffinate from said extract.

It is a further object of my invention to separate an oil into a more paraffinic raffinate phase and a less paraffinic extract phase by means of a selective solvent having relatively high solvent power for high grade material present in the oil and to intermix said extract phase with a selective solvent characterized by a lower solvent power for the high grade material whereby the latter functions as an anti-solvent and an intermediate raffinate is rejected from said extract.

It is another object of my invention to recover an intermediate raffinate from said extract by mixing the extract phase with a liquid, normally gaseous anti-solvent and employing said anti-solvent as an internal refrigerant to aid in reducing the temperature of the extract phase to promote the separation of the intermediate raffinate.

The refrigeration of the extract phase for re-

jection of intermediate raffinate can also be omitted or reduced in degree by removing a considerable portion of the selective solvent from the extract phase before treating the extract phase with an anti-solvent at the temperature appropriate for separation of the relatively paraffinic fractions. In addition to the effect of the anti-solvent, the solubility of the relatively valuable paraffinic fractions in the extract is reduced by the presence of a lower proportion of selective solvent. In some cases, unless the proportion of solvent in the extract phase is reduced, excessively large amounts of anti-solvent must be added to cause phase separation of the extract phase and rejection of an intermediate raffinate.

Therefore, it is another object of my invention to separate an oil by means of a selective solvent into a raffinate and an extract, remove a portion of the selective solvent from the extract phase and then intermix said extract with an anti-solvent to separate an intermediate raffinate from the extract phase.

The figure is a schematic arrangement of one form of apparatus which may be employed to carry out my process.

Referring to the figure, oil enters the system via line 10 controlled by valve 11 by action of pump 12 and passes into primary extractor 13, wherein it is countercurrently extracted with selective solvent introduced through line 14 controlled by valve 15 by action of pump 16. Raffinate phase from extractor 13 is removed via line 17 and valve 18 and passes through coil 20 in heater 21 prior to entrance into secondary extractor 23 via line 24. Countercurrent extraction is again accomplished in 23 by selective solvent introduced through line 25 controlled by valve 26 by action of pump 27. Raffinate phase issues from extractor 23 through 30 controlled by valve 31 and passes through coil 32 in heater 33 and line 34 connected with vapor separator 35. Its temperature is raised sufficiently in 32 to vaporize in 35 the selective solvent associated therewith and these vapors are removed through line 36 controlled by valve 37. High grade raffinate exits via line 38 and valve 39. Intermediate extract phase is removed from secondary extractor 23 through line 40 controlled by valve 41 by action of pump 42.

When the same solvent or a different solvent of substantially the same or lower solvent power is employed in both extractors 13 and 23, the raffinate from the primary extractor is preferably heated before extraction in the secondary extractor in order to increase the amount of intermediate extract produced in the secondary extractor. When the solvent employed in 23 has greater solvent power than the solvent used in 13, heater 21 may be omitted in some cases.

Extract phase from primary extractor 13 passes through line 45 controlled by valve 46. When it is desired to lower the proportion of selective solvent in the extract phase prior to the addition of the anti-solvent thereto, valve 47 in line 45 may be entirely closed in order to by-pass the stream of extract phase via line 48 and valve 49. In this event, the extract phase flows through coil 50, disposed in heat exchange relationship with the material flowing through coil 63, thence passes via line 51 through coil 52 situated in heater 53, after which it travels through line 54 into vaporizer 55. Sufficient heat is imparted to the extract phase to cause vaporization of the desired amount of selective solvent therefrom in 55. These vapors pass from the system via line 56, 75

controlled by valve 51. The extract phase containing the desired proportion of selective solvent passes from vaporizer 55 through line 60 controlled by valve 61 by action of pump 62. It 5 then passes through coil 63 in heat exchange relationship with coil 50. The material then flows through line 64 and valve 65. The temperature of the extract phase may be further lowered by other cooling if desired before introduction of 10 the anti-solvent. Line 64 connects with line 45. In order to avoid heating the total amount of extract phase produced in extractor 13, valves 47 and 49 may be controlled so that only a portion of the extract passing through line 45 is by-passed 15 through line 48 and the heating system. Sufficient solvent is then removed in 55 so that when the streams of extract flowing through lines 64 and 45 are reunited, the mixture will comprise the desired proportion of solvent. In some cases 20 it may not be necessary to lower the proportion of solvent to oil in the extract phase passing from extractor 13 via line 45 before the addition of the anti-solvent. In that event valves 49 and 65 are closed and valve 47 remains open.

25 Anti-solvent is introduced into the stream of extract flowing through line 45 by line 10 controlled by valve 71 by action of pump 72. The combined stream passes into orifice mixer 73 where thorough agitation occurs, after which it 30 passes into cooler 75 via line 14. Cooling may be accomplished by any desired means such as by external refrigeration but when liquid, normally gaseous anti-solvent is employed I prefer to employ internal refrigeration. That is, the 35 pressure is sufficiently reduced in cooler 75 to vaporize a portion of the anti-solvent with consequent cooling of the remaining liquid. The vaporized portion of the anti-solvent exits from cooler 75 through line 76 controlled by valve 77. 40 The extract phase and anti-solvent are sufficiently cooled in 75 to cause phase separation in separator 80 to which the chilled mixture passes by action of pump 81 through line 82 controlled by valve 83. Extract phase from 80 passes through line 84 controlled by valve 85, through heater 86 45 and line 87 into vapor separator 88. The stream is sufficiently heated in 86 to vaporize the anti-solvent and the selective solvent. These vapors pass through exit line 89 controlled by valve 90. The low grade extract oil is removed through line 91 controlled by valve 92.

50 Raffinate phase rejected in separator 80 passes through line 93 controlled by valve 94 through heater 95 and line 96 into vapor separator 97. Sufficient heat is imparted in 95 to vaporize the 55 anti-solvent and any selective solvent associated with the intermediate grade raffinate. These vapors are removed through line 98 controlled by valve 99. In some cases it is desired to heat sufficiently to remove only the anti-solvent from the oil and solvent in vapor separator 97. The intermediate grade raffinate exits from 97 through line 100 controlled by valve 101 by action of pump 102.

60 Although the intermediate grade raffinate flowing through line 100 and the intermediate grade extract produced in secondary extractor 23 may be separately recovered and separately distilled to obtain final products within the desired boiling 65 point range, I prefer to intermix these streams flowing through lines 100 and 40. This combined stream is heated in heater 105 prior to passage into fractionating tower 106 via line 107. Fractionating tower 106 may be provided with the 70 usual trays 108 and other usual appurtenances.

Vapors exit from fractionating tower 106 via line 109 controlled by valve 110. Residual oil passes from the tower through line 111 controlled by valve 112. Intermediate side cut distillates can be taken from tower 106 by lines 113 and 114 5 controlled by valves 115 and 116 respectively. Fractionation in 106 may be accomplished under vacuum and/or with steam injection as desired.

As an example of the operation of the apparatus disclosed in the figure, a dewaxed Santa Fe 10 Springs lubricating distillate characterized by A. P. I. gravity at 60° F. of 19.8°, carbon residue of 0.24%, acid number of 0.16 and viscosity gravity constant of 0.874 was extracted in extractor 13 with 175 volume percent. chloraniline at 45° 15 F. The raffinate thus produced was heated in coil 20 to 80° F. at which temperature extraction in 23 with 120 volume percent. chloraniline was conducted. The high grade raffinate passing from the system via line 38 was characterized by a 20 gravity of 29.9° A. P. I., carbon residue of 0.01%, acid number of 0.04 and viscosity gravity constant of 0.804.

Sufficient extract phase passing from extractor 13 was bypassed via line 48 through heater 52 25 and vapor separator 55 so that upon re-uniting with the stream passing through valve 47 the combined stream comprised 70 volume percent. chloraniline based on the original charge of oil. To this stream was added 105 volume percent. 30 liquid propane as an anti-solvent. Sufficient propane was vaporized in cooler 75 to reduce the temperature of the mixture to 40° F. at which phase separation occurred. Extract removed via line 91 had an A. P. I. gravity at 60° F. of 7.3. 35 Rejected intermediate raffinate freed of propane and chloraniline passing through line 100 had an A. P. I. gravity at 60° F. of 21.9 carbon residue of 0.16%, acid number of 0.04 and viscosity gravity constant of 0.857. In one modified operation, 40 only the propane was vaporized from the intermediate rejected raffinate in 97 and the unvaporized residue in line 100 was combined with the intermediate extract passing through line 40. 45 The mixture was distilled under vacuum into separate cuts of desired boiling point range in heater 105 and fractionating tower 106.

As a further modification of my process, extractor 23 may be omitted in some cases, all of the extraction taking place in 13. In this event, 50 heater 21 is employed to distill the selective solvent from the raffinate passing through line 17.

It will be understood that the foregoing is merely illustrative of certain embodiments of my invention and that many modifications may be 55 made therein without departing from the spirit of my invention.

I claim:

1. A process for the separation of paraffinic and non-paraffinic fractions from mineral oil containing the same which comprises extracting said oil with a selective solvent, separating the extract phase soluble in said solvent from the raffinate phase insoluble therein, reducing the selective solvent content of said extract phase, then commingling said extract phase with an anti-solvent and separating from said extract phase an intermediate raffinate rendered insoluble in said extract phase by said anti-solvent said intermediate raffinate containing the bulk of said anti-solvent. 60

2. A process for the separation of paraffinic and non-paraffinic fractions from mineral oil containing the same which comprises extracting said oil with a selective solvent, separating the extract phase soluble in said solvent from the 65

raffinate phase insoluble therein, reducing the selective solvent content of said extract phase, then commingling said extract phase with an anti-solvent, cooling said extract phase, and separating 5 from said extract phase an intermediate raffinate rendered insoluble in said extract phase by said anti-solvent said intermediate raffinate containing the bulk of said anti-solvent.

3. A process for the separation of paraffinic 10 and non-paraffinic fractions from mineral oil containing the same which comprises extracting said oil with a selective solvent, separating the extract phase soluble in said solvent from the raffinate phase insoluble therein, reducing the selective solvent content of said extract phase, then commingling said extract phase with a liquid, normally gaseous anti-solvent, vaporizing a portion of said anti-solvent, cooling said extract phase by internal refrigeration and separating 15 20 from said extract phase an intermediate raffinate rendered insoluble in said extract phase by said anti-solvent said intermediate raffinate containing the bulk of said anti-solvent.

4. A process for the separation of paraffinic and 25 non-paraffinic fractions from mineral oil containing the same which comprises extracting said oil with a selective solvent, separating the ex-

tract phase soluble in said solvent from the raffinate phase insoluble therein, commingling said extract phase with a liquid, normally gaseous anti-solvent, vaporizing a portion of said anti-solvent, cooling said extract phase by internal refrigeration and separating from said extract phase an intermediate raffinate rendered insoluble in said extract phase by said anti-solvent said intermediate raffinate containing the bulk of said anti-solvent.

5. A process for the separation of paraffinic and non-paraffinic fractions from mineral oil containing the same which comprises extracting said oil with a selective solvent, separating the extract phase soluble in said solvent from the raffinate phase insoluble therein, heating a portion of said extract phase to vaporize solvent, removing said vapors from said heated portion, intermixing the unheated portion of said extract phase with the heated portion, commingling said extract phase with an anti-solvent and separating from said extract phase an intermediate raffinate rendered insoluble in said extract phase by said anti-solvent said intermediate raffinate containing the bulk of said anti-solvent.
